UNITED STATES PATENT OFFICE

JAMES L. HAYES, OF OTTAWA, ILLINOIS

INNER TUBE

Application filed July 17, 1929. Serial No. 379,047.

The present invention is directed to improvements in inner tubes for pneumatic tires.

The primary object of the invention is to provide an article of this character so constructed that when the tire becomes under inflated or totally deflated, the driver will be made cognizant of the fact, owing to a bumping effect imparted to the wheel.

10 Another object of the invention is to provide an article of this kind so constructed that the under inflation of the tube will be readily noticeable without the necessity of using a testing gauge.

15 Another object of the invention is to provide a tube constructed in such manner that the driver will know instantly when the tube is under inflated or totally deflated, thus preventing riding on an under inflated tire which, as is well known, will be subjected to 20 bruises and rim cuts, and is generally detrimental to the tire and tube.

With these and other objects in view, this invention resides in the novel features of 25 construction, formation, combination and arrangement of parts to be hereinafter more fully described, claimed and illustrated in the accompanying drawing, in which:

Figure 1 is a cross sectional view taken 30 through the tube.

Figure 2 is a transverse cross sectional view through the tube.

Referring to the drawing, the numeral 1 designates the inner tube which is provided 35 with the usual inflation valve 2, said tube being confined within the usual casing equipped with the conventional form of rim, the rim being secured to the vehicle wheel in the customary manner.

40 At spaced intervals, the inner surface of the tube 1 is provided with opposed projections 3 and 4, the projection carried by the inner circumference of the tube being gradually thickened longitudinally toward its center and being convex in cross section, 45 as at 5.

The projection carried by the outer periphery of the tube is also thickened longitudinally toward its center but is concave in 50 cross section, as at 6.

The respective projections are formed integral with the tube during the manufacture thereof.

I have illustrated two sets of projections which are disposed at opposite points of the 55 tube in order to balance the tire. The number of projections may be increased if desired and, in fact, one set of projections may be used, but the balancing effect would be lost.

Obviously, when the tube is under inflated, the projections will be moved into interfitting relation, that is to say, the concavity of the projections 4 will receive the convex surfaces of the projections 3. Thus, the 65 respective projections will interfit and prevent lateral swaying or swinging of the casing as well as the tube, thus holding the casing and tube in a position to prevent rim cuts of the casing and twisting of the tube. 70 In this manner, the life of the tube and casing will be prolonged.

As soon as the projections engage due to under inflation of the tube, a noticeable bumping action will result, thus notifying 75 the driver that the tire is under inflated.

The size of the projections is such that said projections will in no way interfere with the flexibility of the tube and casing. Therefore, under normal conditions, the 80 presence of the projections is unnoticeable and will in no way affect the riding qualities of the tire.

From the foregoing, it is thought that the operation and many advantages of the 85 herein described invention will be apparent to those skilled in the art without further description, and it will be understood that various changes in the size, shape, proportion, and minor details of construction may 90 be resorted to without departing from the spirit or sacrificing any of the advantages of the invention.

What is claimed is:

1. An inner tube for pneumatic tires provided with interior means for indicating under inflation by causing a bumping of the wheel, the same consisting of opposed projections, each decreasing in thickness from a central point toward opposite ends and sides. 95 100

2. An inner tube for pneumatic tires provided with interior opposed projections forming an integral part of the tube, each projection decreasing in thickness from a central point toward opposite ends and sides.
5. An inner tube for pneumatic tires provided with interior opposed projections, the face of one projection being convex and the opposing face of the coacting projection being concave.
10. An inner tube for pneumatic tires provided with interior opposed projections, the face of one projection being convex and the opposing face of the coacting projection being convex longitudinally and concave transversely.
15. An inner tube for pneumatic tires provided with interior opposed projections, the face of one projection being convex and the opposing face of the coacting projection being convex longitudinally and concave transversely.

In testimony whereof I affix my signature.
JAMES L. HAYES. [L. S.]
